[57] CLAIM

The ornamental design for a combined table and multiple seat unit, substantially as shown and described.

DESCRIPTION

FIG. 1 is a top plan view of a combined table and multiple seat unit showing my design;
 FIG. 2 is a side elevational view; and
 FIG. 3 is an end elevational view thereof;
 FIG. 4 is a top plan view of a modified form of the combined table and multiple seat unit shown in FIG. 1;
 FIG. 5 is a side elevational view; and
 FIG. 6 is an end elevational view thereof.
 The sides and ends not shown are mirror images of the sides and ends shown in FIGS. 2, 3, 5 and 6 respectfully.

FIG. 1

FIG. 2

FIG. 3
